Attorney

UNITED STATES PATENT OFFICE

2,112,795

LOCK FOR ZIPPER BAGS

Arthur C. Strayer, Beaver, Pa.

Application July 3, 1937, Serial No. 151,911

5 Claims. (Cl. 70—68)

This invention relates to bags and particularly to bags designed for containing money or other valuables, such bags being quite commonly used for night depositing service in banks, where the bag containing the money is dropped into a chute at the bank door to be afterwards opened by the proper officials. More particularly the invention relates to a so-called "Zipper" or separable fastener bag in which the mouth of the bag is held closed by separable fasteners engaged with each other upon a movement of the slide in one direction and disengaged by the movement of the slide in the other direction.

The object of this invention is to provide means for positively locking the slide from movement in a direction to permit the opening of the bag and particularly to provide a locking means which embodies a strap riveted to one wall of the bag by a solid or hollow post which, when the bag is closed, extends through both walls of the bag and through the strap, the end of the post being engaged by a key operated locking device, said strap also carrying a pin which extends through a keeper ring formed upon the slide and disposed on the inside face of the strap so that the slide cannot be in any way tampered with or disengaged to permit the opening of the bag.

My invention is illustrated in the accompanying drawing wherein:

Fig. 1 is an elevation of the upper end of a bag provided with a separable fastener and having my improved means for holding the fastener and the bag locked.

Fig. 2 is a section on the line 2—2 of Fig. 1.

Fig. 3 is a section on the line 3—3 of Fig. 1.

Fig. 4 is a fragmentary elevation of a slightly modified form of locking device.

In the drawing I have illustrated a bag such as commonly used for holding money or other valuables and designed for deposit in a bank after the bank is closed. Such bags are usually made of heavy canvas, leather or other suitable material and locked as securely as possible to prevent any unauthorized tampering with the contents. Certain bags of this character are closed by separable fasteners and it is necessary that the slide of this fastener be locked from movement after the bag is closed. A number of different means have been devised for locking these bags from being opened but all of the devices now in use or proposed are open to certain objections which are avoided by the construction illustrated in the drawing.

In the drawing the bag 9 has its mouth closed by the well known separable fastener elements 10

which include the usual slide 11 with the swinging tongue or handle 12. This handle or hasp is slotted at 13 and the slide is formed with a ring 14 which extends up through the slot when the handle is closed down against the members or teeth 11.

Attached to one wall of the bag, as shown in Fig. 1, is a hollow lock-barrel receiving post 15 closed at one end and open at the other, this post being securely attached to one wall of the bag by means to be later stated. This post passes loosely through a large grommet 16 securely attached to the other wall of the bag. The post 15 extends through one end of a strap 17 and holds this end of the strap securely attached to the rear wall of the bag. The free end of this strap carries a large grommet 18. The strap has securely attached thereto an inwardly projecting pin 19 which, when the strap is carried over the slide 11, passes through the eye or ring 14.

Insertable through the grommets 18 and 16 and into the hollow post 15 is a removable locking barrel 20 having a pin tumbler lock and carrying a rotatable bolt at its inner end which, when projected by a key, locks the barrel in engagement within the hollow post 15. When the key is inserted and turned to retract the bolt, the barrel 20 is entirely removed from the hollow post whereupon the strap 17 may be opened, withdrawing the pin 19 from its engagement with the ring 14. The slide 11 may then be shifted from this end of the bag to the opposite end to thus permit the bag to be opened. The wall of the bag may then, if desired, be shifted outward to carry the grommet 16 free of the post 15, though this is not ordinarily necessary.

I have not illustrated the detailed construction of the pin tumbler lock and its bolt carried within the barrel 20 as this form of lock is well known and constitutes no part of my invention except insofar as I use preferably a hollow or tubular post 15 for the reception of this lock.

In Fig. 4, I have shown a simpler and cheaper form of lock in which all of the parts are precisely the same as heretofore described, except that the post 15a is solid and at its extremity has an aperture 21 through which the hasp of a padlock 22 may be placed. Otherwise than this, as above stated, the structure shown in Fig. 4 is precisely the same as that shown in Fig. 1, except that smaller grommets 16 and 18 may be used.

It will be noted that the strap 17 is attached to the bag by one end of the post 15 or by the post 15a so that the strap will resist very great strain. The strap 17, when drawn down to the

position shown in Figs. 3 and 4, is relatively taut and cannot be pulled away so as to remove the pin 19 from the eye or ring 14. Thus the slide 11 is locked absolutely from any longitudinal movement and inasmuch as it is held in a fully closed position there is no possibility of the bag being opened even to a very slight extent, so that small coins or other objects might be discharged therefrom.

It is pointed out that in my structure, the ring 14 is disposed on the slide to extend upward, thus permitting the pin 19, after it is inserted, to be seen and readily guided into place within the ring or eye 14. Eyes or rings have heretofore been provided on the handle of the slide but extending downward through a slot in the slide and the shackle of a padlock has been passed through the openings in the bag and through this ring. This structure is open to the objection that it is, in the first place, difficult to pass the shackle through the eyelets in the bag and through the ring of the slide as it is difficult to keep the ring in alignment with the eyelets and the ring is usually missed when passing the shackle through the grommets or eyelets. Furthermore, this construction does not prevent the slide from pulling back partially, which allows of the extraction of small coins from the bag. The insertion of a padlock through eyelets is rather difficult to accomplish because the lock shackles must be made rather small in order to eliminate bulk on the bag which is also small. In my construction, I have provided a strap which locks the Zipper slide in immovable position, this leather strap furthermore protecting the ring on top of the Zipper so that this ring cannot be used where pressure might break it off. The strap is so attached that it cannot easily be disengaged by ripping the threads in a sewed on strap or by strain as it is held in position entirely by metal eyelets and attached to metal. Furthermore, I have provided a pin connection insertable into the top ring on the Zipper slide which connection is practically automatic as it comes into position for insertion as the strap is pulled over the top of the slide. Preferably I use a paracentric lock 20 receivable within the post 15, this lock being particularly strong and suitable for the purpose. The bag fastening means which I have devised cannot be opened without showing evidence of tampering and it is equal in security to a metal or lead seal.

The post 15 must be held firmly in place on the rear wall of the bag so that it cannot be detached. I have found that in actual manufacture, it is best for this purpose to have the post 15 pass through an eyelet in the rear wall of the bag and then force a second eyelet between the clenched eyelet and the post clenching this second eyelet against the expanded rear end of the post. This prevents any possible removal of the post without practically destroying the bag. However, any means may be used which will permanently secure the post to the bag and prevent any easy detachment therefrom.

What is claimed is:—

1. In a bag having coacting separable fastening members on the opposed edges of the bag and a slide coacting therewith, the slide having an upwardly projecting ring; a locking means therefor including a post permanently attached to the rear wall of the bag, the front wall of the bag having an aperture through which the post passes when the bag is closed, key operated means engageable with the post, and a strap per-

manently attached to the outer face of the rear wall of the bag and having an opening at its free end adapted to engage over said post, the strap on its inside face having a projecting pin for passage through the ring on the slide when the strap is drawn across the mouth of the bag with the mouth closed and the aperture of the strap engaging over the post. 5

2. In a bag having separable fastening elements at its mouth and a slide coacting therewith, the slide having an upwardly projecting ring and a hinged handle slotted to receive said ring when the handle is closed down against the slide; locking means therefor including a hollow post permanently attached to the rear wall of the bag 15 and open at its outer end, the front wall having a grommet through which the post passes when the bag is closed, a strap permanently attached to the outer face of the rear wall of the bag, the free end of the strap having a grommet 20 adapted to be disposed over said post, the inside face of the strap having a projecting pin adapted to be passed through the ring on the slide when the strap is drawn across the mouth of the bag with the mouth closed and the grommet of the 25 strap engaging over the post, and a locking element engageable with the free end of the post and holding the strap in locked position upon said post.

3. In a bag having separable fastening elements at its mouth and a slide coacting therewith, the slide having an upwardly projecting ring and a hinged handle slotted to receive said ring when the handle is closed down against the slide; locking means therefor including a hollow post permanently attached to the rear wall of the bag and open at its outer end, the front wall of the bag having a grommeted opening 35 through which the post may be passed, a strap permanently and securely attached to the outer 40 face of the rear wall at one end and having a grommeted aperture at its free end to engage over said post, the inside face of the strap having a projecting pin for passage through the ring on the slide when the strap is drawn across the 45 mouth of the bag with the mouth closed, and a locking member insertable into the open end of the post and locking therein, the locking member when inserted holding the free end of the strap in engagement with the post. 50

4. In a bag of the character described, having separable fastening elements at its mouth and a slide coacting therewith, the slide having an upwardly projecting ring and a hinged handle having a slot through which the ring is passed 55 when the handle is closed; locking means therefor including a post permanently attached to the rear wall of the bag, the extremity of the post being apertured, the front wall of the bag having a grommeted aperture through which the post 60 passes when the bag is closed, a strap having one end permanently attached to the outer face of the rear wall of the bag by said post, the free end of the strap having a grommeted opening adapted to engage said post, the strap on its inner face having an inwardly projecting pin 65 adapted to be passed through the ring on the slide when the strap is drawn across the mouth of the bag with the mouth closed, and a locking device including a shackle passing through the 70 slot in the extremity of the post.

5. In a bag of the character described, having separable fastener elements at its mouth and a slide coacting therewith, the slide having an upwardly projecting ring; locking means including 75

a post permanently attached to the rear wall of the bag, the front wall having a grommeted aperture through which the post passes when the bag is closed, a strap having one end permanently attached to the outer face of the rear wall of the bag by said post, the strap having a grommeted aperture at its free end for engagement over the extremity of the post and having a pro-

jecting pin midway of its ends for passage through the ring on the slide when the strap is drawn across the mouth of the bag and the mouth closed, and a locking element engaging with the post and when engaged extending across the strap. 5
